(57) **CLAIM**

The ornamental design for an anchor spade attachment, as shown and described.

DESCRIPTION

FIG. 1 is a front top left perspective view of an anchor spade attachment;

FIG. 2 is a rear bottom right perspective view thereof;

FIG. 3 is a front elevational view thereof, where the rear elevational view is identical thereto;

FIG. 4 is a top plan view thereof;

FIG. 5 is a bottom plan view thereof;

FIG. 6 is a left elevational view thereof; and,

FIG. 7 is a right elevational view.

The broken lines in FIGS. 1-3 and 5-7 are included for the purpose of illustrating environmental structure and forms no part of the claimed design.
